INVENTOR.
MAURICE P. KOCH
BY George B. White
ATTORNEY.

3. A luggage sealing device for use on a luggage body having a top side and a bottom side, the device comprising a female sealing strip having a slot extending from its bottom edge to a suitable height, the width of the slot slidably fitting over the top edge of the side, and a male sealing strip having a slot extending from its bottom edge to a suitable height, the width of the slot slidably fitting over the bottom edge of the side, the female strip being secured to the top edge of the side and the male strip being secured to the bottom edge of the side, the top edge of the male strip being offset with respect to the width of the slot so as to leave a slight space for a suitable cement for fixing the strip in place.

UNITED STATES PATENT OFFICE

2,604,961

LUGGAGE SEALING DEVICE

Maurice P. Koch, San Francisco, Calif.

Application April 17, 1950, Serial No. 156,357

3 Claims. (Cl. 190—28)

1

This invention relates to a sealed luggage.

The primary object of this invention is to provide coacting sealing edges on a luggage which interlock in such a manner as to positively prevent the passage of moisture of any kind therethrough into or out of the luggage.

Particularly it is an object of this invention to provide an edge strip for the lower portion of the luggage, and a complementary edge strip on the cover edges of the luggage so that the edge strips telescope into one another when the luggage is closed, and a resiliently compressible seal within the joint between said strips; said strips being adapted to straddle the respective edges and to form a moisture proof union with walls of the luggage at said respective edges.

I am aware that some changes may be made in the general arrangements and combinations of the several devices and parts, as well as in the details of the construction thereof without departing from the scope of the present invention as set forth in the following specification, and as defined in the following claims; hence I do not limit my invention to the exact arrangements and combinations of the said device and parts as described in the said specification, nor do I confine myself to the exact details of the construction of the said parts as illustrated in the accompanying drawing.

With the foregoing and other objects in view, which will be made manifest in the following detailed description, reference is had to the accompanying drawing for the illustrative embodiment of the invention, wherein:

Fig. 1 is a fragmental perspective view of a corner of the luggage showing the top or cover partly raised, and

Fig. 2 is a sectional view of a side of the luggage the cover being in closed position.

In the herein illustration my invention is shown in use on a luggage made of waterproof and moistureproof materials, which are light but strong, for instance molded from so called fiber glass sheets.

The body 1 of the luggage has integral sides 2. The cover 3 has complementary integral sides 4 arranged at angles to fit over the sides 2 of the luggage body 1. The cover is swingably attachable to the body in any suitable manner (not shown).

On the top edges 6 of each side 2 of the body 1 is secured a continuous female sealing strip 7. This female sealing strip 7 is made of a suitable light and waterproof material. The strip 7 has a slot 8 extending from its bottom 9 to a suitable height. The width of the slot 8 slidably fits over

2

the top of the side 2 of the luggage body 1, so as to leave a slight space for a suitable cement for fixing the strip in place.

The strip 7 thus straddles the top of the side 2. The slot 8 is offset with respect to the width of the strip 7 so that it is nearer to the inner surface 9 than to the outer or exposed surface 11 of the strip 7. In other words, the exposed leg 12 of the strip 7 is thicker than the inside leg 13, as the legs straddle the top of the side 2 and extend over the respective surfaces of said side 2.

In the top of the female strip 7 is formed a longitudinal substantially generally V-shaped groove 14 which extends along the full length of the female strip 7. At the apex of the V-shaped groove 14 is a channel 16 of generally circular cross section connected to the V-shaped groove 14 by a mouth slit 17. A resiliently compressible generally cylindrical packing strip 18 is packed into said channel 16 so that the packing strip 18 projects through the mouth slit 17 into the apex of the V-shaped slot 14.

The top or cover seal is a male sealing strip 19, which has a straddling slot 21 fitting over the edges of the cover sides 4, similarly to the fitting of the female strip 7 over the bottom sides 2. The slot 21 is offset to one side symmetrically to the relative lateral offset of the slot 8 in the female strip 7, so that the exposed leg 22 is thicker than the inside leg 23, and each preferably being of the same thickness as the respective legs 12 and 13 of the female sealing strip 7.

From the edge of the male strip 19 farthest from the slot 21 extends a sealing rib 24, which has sides converging from the strip 19 toward the free tip or edge of the rib 24 at about the same relative angle as the angles of inclines of the respective sides of the V-shaped groove 14 of the female strip 7.

The V-shaped groove 14 has its base or wider end spaced from the opposite side surfaces 9 and 11 of the female strip 7 so as to form ledges 26 of equal width on each side of the base of the V-shaped groove 14.

On each side of the base of the male rib 24 is formed a ledge 27 which are also of equal width. The total width of the male strip 19 is the same as that of the female strip 7 so that the exposed surfaces and inside surfaces of the strips are in registry when the luggage is closed. The distance from the base of the rib 24 to its rounded tip or apex 28 is slightly larger than the distance from the base of the groove 14 to the mouth slit 17, so that the rounded tip 28 of the rib 24 projects through said slit 17 and into the channel 16 for compressing the packing strip 18 tightly against

the sides of the channel 16. This relative depth of the rib 24 and the groove 14 also leaves a slight space between the respective opposite ledges 26 and 27.

The sealing edges herein described are furnished in strips which can be cut or formed into suitable lengths and shapes to follow the contour of the exposed edges of the respective parts of a luggage, and to form a continuous sealing strip around the opposite edges of the luggage. As the cover is closed tight the male rib 24 penetrates through the mouth slit 17 and is pressed against the packing strip 18. By providing a luggage the walls of which are made of moisture proof material, the herein described coacting sealing strips can render luggage completely moistureproof, waterproof and practically hermetically sealed.

I claim:

1. In a sealing device for the meeting edges of separable parts of a luggage, a female strip adapted to be secured over the edges of one of said separable parts, a male strip adapted to be secured over the edges of the other separable part, said female strip having a longitudinal groove in its edge facing said male strip, said groove being substantially of V-shape cross section, a longitudinal rib on the edge of the male strip facing said female strip and fitting into said groove, a continuous generally cylindrical channel formed along about the apex of said groove, said rib being higher than the distance from the base of the groove to said channel, and a resiliently compressible packing strip in said channel, said packing strip being of substantially the same diameter as the diameter of the channel so that it projects above said channel and into said groove in its expanded state; each of said strips having a longitudinal slot therein adapted to straddle the edges of a luggage, said slot being offset in each strip toward the inside of said strip to leave a thicker leg for the outside of the luggage.

2. In a sealing device for the meeting edges of separable parts of a luggage, a female strip adapted to be secured over the edges of one of

said separable parts, a male strip adapted to be secured over the edges of the other separable part, said female strip having a longitudinal groove in its edge facing said male strip, said groove being substantially of V-shape cross section, a longitudinal rib on the edge of the male strip facing said female strip and fitting into said groove, a continuous generally cylindrical channel formed along about the apex of said groove, said rib being higher than the distance from the base of the groove to said channel, and a resiliently compressible packing strip in said channel being substantially of the same diameter as said channel so that said packing strip projects above said channel and into said groove.

3. A sealing device for luggage comprising a female strip adapted to be secured over the edges of one part of the luggage, and a male strip adapted to be secured over the edges of the complementary part of the luggage, said female strip having a longitudinal groove in its edge opposite said male strip, a rib on the edge of the male strip fitting into said groove, and a resiliently compressible packing strip in the bottom of said groove engageable by said rib, each of said strips having a slot in its edge farthest from the other strip, said slot being adapted to straddle the respective edges of said luggage, said slot being offset in each strip toward the inside face of the strip to leave a thicker leg on the outside of the luggage.
